UNITED STATES PATENT OFFICE.

ANTOINE LACROIX, JR., OF BROOKLYN, ASSIGNOR TO THE CO-OPERATIVE BUILDING PLAN ASSOCIATION, OF NEW YORK, N. Y.

DESIGN FOR THE EXTERIOR OF A HOUSE.

SPECIFICATION forming part of Design No. 20,088, dated August 12, 1890.

Application filed July 15, 1890. Serial No. 358,851. Term of patent 7 years.

To all whom it may concern:

Be it known that I, ANTOINE LACROIX, Jr., of the city of Brooklyn, in the county of Kings and State of New York, have invented and 5 produced a new and original Design for the Exterior of a House, of which the following is a specification, reference being had to the accompanying drawings, forming a part thereof.

Figure 1 represents a perspective view of a 10 house showing my design. Fig. 2 represents a horizontal section or plan of the first story. Fig. 3 represents a horizontal section or plan of the second story.

Similar letters of reference designate corresponding parts in all the figures.

A house of this design consists of two stories with an attic third story contained within a hip roof, and has a rearwardly-projecting two-story extension, also having a hip roof, a 20 flat-faced bay on one side and an octagonal bay on the opposite side thereof to the two stories, and an octagonal bay in one corner at the front extending upwardly beyond the eaves of the said roof, forming thereby a third 25 story, and surmounted by a peaked roof or spire, a portion of the front and one side having a veranda at the first story covered by a sloping roof and a veranda at the second story extending along the front from one side 30 thereof to the angle formed by the bay with the front, all as hereinafter more particularly described with reference to the drawings.

A B C designate the exterior of the first and second stories and attic which are partially contained in a two-story extension D, surmounted by a hip roof d. The main portion of the house is surmounted by a hip roof E, from which dormer-windows a, having roofs b, project. One side of the house has a flat-faced bay F projecting from the first and 40 second stories, and an octagonal bay G on the opposite side thereof surmounted by a peaked roof g. The front of the house at one corner thereof has an octagonal bay H extending upwardly for three stories, and is 45 surmounted by a peaked roof or spire h. A veranda I, having a sloping roof i, extends along a portion of the front and one side of the house at the first story, and at the second story a veranda J extends along the front 50 from one side thereof to the octagonal bay H, and is covered by the main roof E. The rear extension also has a veranda L along one side thereof and covered by a shed-roof l.

What I claim as my design is—
The design for the exterior of a house, substantially as herein shown and described.

ANTOINE LACROIX, JR.
